UNITED STATES PATENT OFFICE

172,261

ORNAMENT FOR AN AUTOMOBILE HOOD

Richard F. Baird, Oak Park, Mich., assignor to
Chrysler Corporation, Highland Park, Mich., a
corporation of Delaware

Application May 12, 1953, Serial No. 24,964

Term of patent 7 years

(Cl. D14—18)

To all whom it may concern:

Be it known that I, Richard F. Baird, a citizen of the United States, residing in the city of Oak Park, county of Oakland, and State of Michigan, have invented a new, original, and ornamental Design for an Ornament for an Automobile Hood, of which the following is a specification, reference being had to the accompanying drawings, forming part thereof, in which:

Fig. 1 is a top plan view of an ornament for an automobile hood, showing my new design;

Fig. 2 is a side elevation of the ornament;

Fig. 3 is a front elevation of the ornament; and

Figs. 4, 5, 6 and 7 are sectional views taken on the lines 4—4, 5—5, 6—6 and 7—7 respectively of Fig. 1.

I claim:

The ornamental design for an ornament for an automobile hood, substantially as shown.
